RESISTIVE DEVICE AND METHOD OF
MAKINGCharles J. Ganci, Ridgewood, N. Y., assignor to
Ward Leonard Electric Company, a corpora-
tion of New York

Application August 14, 1943, Serial No. 498,651

6 Claims. (Cl. 201—63)

1

This invention relates to improvements in resistive devices such as tubular resistive units and other forms.

In making resistive units, such as of tubular form, in which a solid conductor, usually in the form of a wire or ribbon, or a conductor of various forms and cross-sections, is utilized as the resistive conductor, it is desirable to provide stranded wire connections thereto, or so-called pigtail leads, owing to their flexibility and convenience in making connections to the circuit in which the device is to be used and owing to their comparative freedom from breaking after repeated bending and twisting. It has been common to twist the stranded wire around the solid wire and solder the connection but this forms an objectionably enlarged joint; and particularly in resistive units wherein the resistive conductor is coated with an insulating coating, the enlarged joint is objectionable not only in increasing the outside dimension of the unit but in the difficulty of properly covering and embedding the joint with the insulating coating.

According to the present invention, the ends of the conductors are butt welded together to produce a joint not appreciably larger than the size of the conductors and give the joined conductors the appearance of a continuous conductor. When a resistive conductor with such welded terminal leads of stranded wire is utilized in a resistive device, there are no enlarged joints to contend with in applying the insulating coating, resulting in a final product having a uniform and smooth appearance throughout. But the butt welding of the end of a stranded wire cannot be accomplished properly if it be attempted to weld by joining the ends of the stranded wire to the end of a conductor; because some of the strands may be welded while others will not. This results in a poor electrical connection and in the spreading out of the unwelded strands or of some of them, giving an awkward joint to properly and fully cover by the insulating coating. It also results in a portion protruding from the unit at the joint. Furthermore, during the maturing of the insulating coating, as by firing in a furnace, the strains imposed on the few welded strands are likely to rupture the connection, giving an open circuit in the completed article. The number of rejects from this cause alone may be considerable. Even if the opening of the circuit does not occur, the few strands remaining connected will, during use of the device, cause excessive heating localized at the joint which is likely to cause a breakdown of the device after a short period of use. The present invention overcomes these various difficulties.

One object of the invention is to produce a resistive device which will be durable and dependable in long continued use. Another object is to

2

obtain a device which will have a uniform and smooth surface throughout its length and substantially overcome rejects in the process of manufacture due to failure of the connection between the conductor and the stranded lead wires. A further object is to produce a process of manufacture which may be conveniently accomplished and carried out with assurance of dependability and durability. Other objects and advantages will be understood from the following description and accompanying drawing which illustrate embodiments of the invention and the steps in the method of making.

Fig. 1 is a side view of a resistive device of tubular form showing the tubular support and the conductor applied thereto before the application of the insulating coating; Fig. 2 is a side view of the completed unit; Fig. 3 is a diagram showing a step in the process of preparing the stranded conductor for welding; Fig. 4 is a diagram showing a further step in the process; Fig. 5 is a similar diagram showing the final step in the process; and Figs. 6, 7 and 8 are side views of joined conductors as illustrative examples.

Referring to Fig. 1, the main support is a tube 1 of insulating material such as porcelain. On this is wound a solid conductor 2 forming the resistive conductor. This is of a proper size, length and number of turns to give the desired resistance to the unit. It may be of any suitable metal or alloy, such as Nichrome composed of nickel, chromium and iron, or may be an alloy of nickel and copper, or of nickel and chromium, various alloys of iron, or any other metal or alloy according to particular requirements.

At each end of the resistive conductor 2 is a joint 3 between it and the stranded wires 4 and 5 forming the flexible terminal connections. The lead 4 continues from its joint 3 around the tube and then passes within the tube through a hole 6 and then out from the end of the tube to form the outside lead. The lead 5 continues from its joint 3 around the tube and then passes within the tube through a notch 7 and through the length of the tube to form the other outside lead.

As to the joint 3, it is shown as a solid connection between the solid conductor 2 and the stranded wire leads 4 and 5; and this joint is no larger than the conductor 2 or the leads, giving the appearance of a continuous conductor of uniform size having no protruding portions or objectionable enlargement. It therefore forms a joint which may be readily and conveniently covered by the insulating coating. In fact it is just as easily and fully covered as any other portions of the conductor. The device as shown in Fig. 1 is ready for the application of the insulating coating which may be of any suitable material but is preferably of vitreous enamel material. The coating is matured by firing in a fur-

nace if of vitreous enamel, and by drying or otherwise according to the character of the coating material.

Fig. 2 shows the completed unit with the insulating coating 8; and it is obvious that the device is of uniform size throughout with a smooth surface and no objectionable protruding portions. This particular resistive unit was for an immersion heater and was adapted to slide into a quite closely fitted tube or casing; any projection from the unit due to enlarged joints or connections between the conductor and leads would prevent it from fitting within the tubular casing. In making the unit, the resistive conductor is first made of proper length and then the stranded wire terminals are joined thereto in the manner later described. The free end of the lead 4 is passed through the hole 6 and then the inner portion of the lead 4 and the conductor 2 is wound around the tube and also a portion of the lead 5. The remaining portion of the lead 5 is then passed through the length of the tube and held in place by being drawn into the notch 7. The insulating coating is then applied.

As to the making of the joint, Fig. 3 shows the first step. A length of stranded wire 9 is clamped between the jaws 10 of a butt welder, a portion of the wire extending between the two pairs of jaws. The welder is supplied with current from a suitable source, such as from the secondary 11 of a transformer 12. The heating is concentrated at the midportion of the stranded wire and fused there, resulting in the separation of the wire to form two separate leads and in a fused solid end 13 on each of the leads, as shown in Fig. 4. This solid fused end is not materially larger or smaller than the size or diameter of the stranded wire and all of the strands are permanently fused and connected to this solid end.

The next step is shown in Fig. 5. Here one of the stranded wires or leads 9 having the fused solid end is placed in one of the jaws of the welder and the solid resistive conductor 2 is placed in the other jaw. One of the jaws is then moved towards the other to bring together the solid end 13 of the lead and the end of the solid conductor. This causes the fusing of the meeting ends giving a solid joint 14, as shown in Fig. 5; and the connection of all of the strands to the solid conductor is insured with a solid joint of about the same size as the larger of the two wires. Another stranded lead is similarly connected to the other end of the solid conductor 2; and the combined conductor is then ready for application to the tube 1, the device being completed in the manner already described.

This method of forming the joint is applicable to the joining of stranded conductors, or multiple conductors, of different sizes to solid conductors of different sizes and shapes. Fig. 6 shows a stranded conductor 15 connected to a solid wire 16 at the joint 17, the wire 16 being of much larger size than the stranded wire. Fig. 7 shows the stranded wire 15 connected at the joint 18 to a solid wire 19 of smaller size. This method of forming the joint is applicable likewise to the joining of two stranded or braided wires or conductors. In that case a solid end is first formed on the ends of each of such conductors in the manner described with reference to Figs. 3 and 4. The fused ends of the two conductors to be joined are then brought to-

gether and fused in the manner described with reference to Fig. 5. A stranded wire 15 thus fused to a larger braided wire 20 is shown as an example in Fig. 8 at the solid joint 21. All strands of each of the two conductors are thus fused to the common joint and insure complete electrical connection between all strands of both conductors.

Although preferred embodiments have been described as illustrative examples, the invention may be embodied in other types and forms of resistive devices and modifications made without departing from the scope of the invention.

I claim:

15. A resistive device comprising an insulating support, a solid resistive conductor carried thereby, and a lead of a stranded conductor joined thereto, the end of the stranded conductor having a fused solid end butting against the end of the solid conductor and fused thereto in a solid joint of a size approximately equal to that of the larger of the two conductors.

20. A resistive device comprising an insulating support, a solid resistive conductor carried thereby, and a lead of a stranded conductor joined thereto, the end of each strand of the stranded conductor being fused into a solid end, and the said solid end being fused to the end of the solid conductor.

25. A resistive device comprising an insulating support, a solid resistive conductor carried thereby, a lead of a stranded conductor joined thereto, the fused solid end of the stranded conductor butting against the end of the solid conductor and fused thereto in a solid joint of a size approximately equal to that of the larger of the two conductors, and an insulating coating covering said resistive conductor and said joint.

30. A resistive device comprising an insulating support, a solid resistive conductor carried thereby, a lead of a stranded conductor joined thereto, the end of each strand of the stranded conductor being fused into a solid end, and the said solid end being fused to the end of the solid conductor, and an insulating coating covering said resistive conductor and said joint.

35. A resistive device comprising an insulating supporting tube, a solid resistive conductor wound thereon, a lead of a stranded conductor joined to each end of said solid conductor respectively, the fused solid ends of the said stranded conductor butting against the ends of said solid conductor and fused thereto in solid joints of a size approximately equal to the size of the larger of the conductors, and an insulating coating covering said solid conductor and covering said joints and portions of each of said stranded conductors.

40. A resistive device comprising an insulating supporting tube, a solid resistive conductor wound thereon, a lead of a stranded conductor joined to each end of said solid conductor respectively, the ends of the said stranded wire being fused to solid ends, and said fused ends butting against the ends of said solid conductor and fused thereto in solid joints of a size approximately equal to the size of the larger of the conductors, and an insulating coating covering said solid conductor and covering said joints and portions of each of said stranded conductors, the 45 uncovered ends of said stranded conductors being passed through openings in said tube to form external leads.
